B. C. SMITH,
FUEL FEEDING APPARATUS.
APPLICATION FILED JUNE 29, 1916.

1,237,964.

Patented Aug. 21, 1917.

UNITED STATES PATENT OFFICE.

BENJAMIN C. SMITH, OF BAYONNE, NEW JERSEY, ASSIGNOR TO STANDARD MOTOR CONSTRUCTION COMPANY, OF JERSEY CITY, NEW JERSEY, A CORPORATION OF NEW JERSEY.

FUEL-FEEDING APPARATUS.

1,237,964.

Specification of Letters Patent. Patented Aug. 21, 1917.

Application filed June 29, 1916. Serial No. 106,550.

To all whom it may concern:

Be it known that I, BENJAMIN C. SMITH, a citizen of the United States of America, residing at Bayonne, Hudson county, New Jersey, have invented a new and useful Fuel-Feeding Apparatus, of which the following is a specification.

My invention relates to improvements in oil burning engines of the high compression type wherein the fuel is injected into the cylinder at the desired period in the cycle thereof. My object is to provide a simple and effective means for feeding fuel to the engine.

15 In the accompanying drawings:

Figure 1 is a vertical sectional view of the upper part of an engine cylinder, certain parts which are associated therewith being shown conventionally.

20 Fig. 2 is a fragmentary similar view showing certain parts in a different position.

It should be understood that the drawings are merely illustrative, and do not pretend to show exact proportions. Furthermore, 25 the said drawings are illustrative of a preferred construction, it being my expectation that various changes and modifications may be made without departing from the spirit and scope of my invention.

30 In that form of the invention shown herein, 1 represents the upper part of an ordinary water jacketed cylinder. 2 represents a piston therein which is connected in the usual manner with the crank shaft, not shown. 3 represents the usual water jacketed cylinder head. 4 conventionally represents an air compressor which leads to a suitable air receiver 5. 6 conventionally represents a fuel supply tank. 7 conventionally

40 represents a fuel controlling means by which the quantity of fuel from the tank 6 to the engine may be controlled, any suitable controlling means being employed. 8 represents a valve in the upper part of the cylinder past which the fuel may be forced at the proper time. This valve is normally held seated or closed by means of a spring 9.

10 is a piston sleeve surrounding the stem of the valve 8. This piston sleeve is movable up and down in what I may term a plug 11 which is mounted in a bore in the cylinder head 3 and which may be held in place in any suitable manner as by bolts 12-12. The piston sleeve 10 may have suitable packing 55 rings 13. The stem of the valve 8 is pro-

vided near its lower end with a shoulder 14 against which the lower end of the piston sleeve 10 may strike near the end of its downward movement to cause the valve 8 to open. The piston sleeve 10 is moved up and down by the operation of the engine through the medium of any suitable means operating at the proper period and in the cycle of the engine. In this particular instance, 15 represents an engine controlled rocker arm suitably connected with the piston sleeve 10 to cause the latter to move up and down. 16 is an air duct leading from the compressor 4 through the receiver 5 to the plug 11 wherein said duct has an opening at one side 70 of the bore in which the piston sleeve 10 reciprocates, the said opening occurring at approximately 17, whereby when the piston sleeve 10 is raised, it will uncover the opening 17 and let compressed air into the space 75 below the piston. 18 is a fuel pipe leading from the supply 6 through the controller 7 and into the plug 11, the said plug having a bore in communication with said pipe, which bore opens at the bottom of the bore in 80 which the piston sleeve 10 moves. This opening for the fuel is indicated at 19. 20 is a suitable back check valve in the fuel line. 21 conventionally represents an air inlet valve for the cylinder, which valve operates 85 to admit air into the cylinder on the descent of the piston 2. The check valve 20 may be of any desired type and may have a light spring 22 which may assist in closing the same at the proper time. The plug 11, of 90 course, should have a gas tight fit in the piston head, and one simple way of securing said fit is to taper the lower end of the plug and to provide a correspondingly tapered seat in the lower end of the bore in 95 the piston head in which said plug is located. The tapered seats may be provided with any suitable packing or may form a so-called ground joint.

Operation: With the parts in the position shown, it may be assumed that the piston 2 is at or near the top of its stroke in cylinder 1, with the air in the cylinder under substantially maximum compression, at which time it is desirable that the fuel should be injected. The piston sleeve 10 is descending. It may be assumed that the space below the piston sleeve 10 contains very highly compressed air and a suitable volume of fuel. The slight further descent of the pis- 100

105

110

ton sleeve 10 will shift the latter from the position shown in Fig. 1 to the position shown in Fig. 2, whereupon the valve 8 will be opened and the highly compressed air and fuel will be forced past the same into the space above the piston within the cylinder. For this purpose it is obvious that the pressure of air in the pipe line 16 should be in excess of the pressure in the cylinder above the piston at the moment of injection, otherwise, of course, there would be no forceful feeding of the fuel into the space above the piston. The particular difference in pressure in the pipe line 16 and in the cylinder may vary under varying conditions, and, therefore, I do not wish to be limited in this respect, excepting in so far as it is understood that the air pressure in the pipe 16 should be sufficiently high so that the air pressure under the piston sleeve 10 when said air is admitted, plus the further increase in compression due to the descent of the piston sleeve 10, will be sufficient to force the fuel past the valve 8 into the cylinder. When the piston sleeve 10 ascends, the valve 8 closes, and upon the ascent of said piston sleeve fuel through the pipe line 18 is delivered in the proper quantity to the space around the stem of the valve 8 and below the piston sleeve 10. When the latter has ascended sufficiently high to uncover the air opening 17, another charge of air is forced into the space below the piston sleeve 10 so that the new charge of fuel will be forced into the combustion chamber of the cylinder on the next descent of the piston sleeve 10, as before described. The check valve 20 prevents this high pressure from forcing back the fuel in the pipe line 18 during the descent of the piston sleeve 10.

Since my invention relates chiefly to the fuel feeding plug, as I may term it, it is obvious that the said invention should not be limited to an engine of either the four cycle or the two cycle type, since it can be employed successfully with either, although for the purposes of this application, I have it associated with an engine which may be assumed to be of the four cycle variety. I have not shown the usual exhaust valve, the construction and operation of such a valve being too well known to require illustration, and constituting no part of this invention.

It will be understood that any suitable means or method may be employed for operating the valve 8. In some instances the pressure in the bore on the feeding stroke of the piston 10 might be sufficient to cause said valve to unseat against the pressure in the working cylinder 1 before the piston 10 reaches the shoulder 14, but when it is desired to provide means for positively insuring the opening of the valve, additional means may be employed, such as the shoulder 14 designed to be engaged just be-

fore the piston 10 reaches its full forward movement.

What I claim is:

1. In a fuel feeding apparatus for internal combustion engines, an engine driven fuel feeding piston, a mounting therefor having a bore in which said piston reciprocates, a fuel feeding passage arranged to lead from said bore to an engine cylinder, a valve for said passage with means for closing the same, a compressed air inlet in said mounting leading into said bore adjacent to the end of the fuel feeding piston at the back of its stroke, a fuel feeding inlet into said bore between said compressed air inlet and said valve, said piston coöperating with said valve to open the latter.

2. In a fuel feeding apparatus for internal combustion engines, an engine driven fuel feeding piston, a mounting therefor having a bore in which said piston reciprocates, a fuel feeding passage arranged to lead from said bore to an engine cylinder, a valve for said passage with means for closing the same, a compressed air inlet in said mounting leading into said bore adjacent to the end of the fuel feeding piston at the back of its stroke, a fuel feeding inlet into said bore between said compressed air inlet and said valve, said piston coöperating with said valve to open the latter, with means for forcing compressed air into said bore through said air inlet when the fuel feeding piston is at the back of its stroke.

3. In a fuel feeding apparatus for internal combustion engines, an engine driven fuel feeding piston, a mounting therefor having a bore in which said piston reciprocates, a fuel feeding passage arranged to lead from said bore to an engine cylinder, a valve for said passage with means for closing the same, a compressed air inlet in said mounting leading into said bore adjacent to the end of the fuel feeding piston at the back of its stroke, a fuel feeding inlet into said bore between said compressed air inlet and said valve, with means for feeding fuel through the fuel inlet into said bore while said fuel feeding piston is retracted, said valve being opened by pressure applied to the same from within the bore.

4. In a fuel feeding apparatus for internal combustion engines, an engine driven fuel feeding piston, a mounting therefor having a bore in which said piston reciprocates, a fuel feeding passage arranged to lead from said bore to an engine cylinder, a valve for said passage with means for closing the same, a compressed air inlet in said mounting leading into said bore adjacent to the end of the fuel feeding piston at the back of its stroke, a fuel feeding inlet into said bore between said compressed air inlet and said valve, said fuel feeding piston coöperating with said valve to open the same.

near the end of its forward or feeding stroke.

5. In a fuel feeding apparatus for internal combustion engines, an engine driven fuel feeding piston, a mounting therefor having a bore in which said piston reciprocates, a fuel feeding passage arranged to lead from said bore to an engine cylinder, a valve for said passage with means for closing the 10 same, a compressed air inlet in said mounting leading into said bore adjacent to the end of the fuel feeding piston at the back of its stroke, a fuel feeding inlet into said bore between said compressed air inlet and said valve, said fuel feeding piston coöperating with said valve to open the same near the end of its forward or feeding stroke, said valve having a shoulder against which said piston engages before it reaches the 20 end of its forward stroke.

6. In a fuel feeding apparatus for internal combustion engines, an engine driven fuel feeding piston, a mounting therefor, having a bore in which said piston reciprocates, a 25 passage through said fuel feeding piston, a valve for the lower end of said bore, the stem of the valve passing through the bore in the piston with means for normally causing said valve to close the outlet at the fuel 30 discharge end of the bore, a compressed air inlet leading through said mounting and into the bore thereof adjacent to the end of the piston when the latter is retracted, a fuel feeding inlet into said bore located between the air inlet and said valve, said valve opening in the direction of movement of said piston on its compression stroke.

7. In a fuel feeding apparatus for internal combustion engines, an engine driven fuel 40 feeding piston, a mounting therefor, having a bore in which said piston reciprocates, a passage through said fuel feeding piston, a valve for the lower end of said bore, the stem of the valve passing through the bore 45 in the piston with means for normally causing said valve to close the outlet at the fuel discharge end of the bore, a compressed air inlet leading through said mounting and into the bore thereof adjacent to the end 50 of the piston when the latter is retracted, a fuel feeding inlet located between the air inlet and said valve, means for feeding compressed air through the compressed air inlet when the fuel feeding piston is re' 55 and means for feeding fuel through the fuel

inlet into said bore while said piston is being retracted, said piston operating to open said valve near the end of its compression stroke.

8. In a fuel feeding apparatus for internal combustion engines, an engine driven fuel 60 feeding piston, a mounting therefor, having a bore in which said piston reciprocates, a passage through said fuel feeding piston, a valve for the lower end of said bore, the stem of the valve passing through the bore 65 in the piston with means for normally causing said valve to close the outlet at the fuel discharge end of the bore, a compressed air inlet leading through said mounting and into the bore thereof adjacent to the end 70 of the piston when the latter is retracted, a fuel feeding inlet located between the air inlet and said valve, means for feeding compressed air through the compressed air inlet when the fuel feeding piston is re- 75

9. In a fuel feeding apparatus for internal 80 combustion engines, a working cylinder, a working piston therein, a fuel feeding valve, a mounting therefor having a bore to snugly receive said fuel feeding piston, and a communicating passage between said bore and 85 the interior of the working cylinder above the piston, a valve for said passage normally closed, a compressed air inlet communicating with said bore at a point near the end of the fuel feeding piston at the 90 end of its back stroke, a fuel inlet leading through said mounting and into said bore near the discharge end thereof, with means for forcing compressed air through the air inlet when the piston is retracted, and means 95 for feeding fuel through the fuel passage when said fuel feeding piston is retracted, the air passage and the fuel passage being closed on the forward or feeding stroke of said fuel feeding piston, a spring for holding said valve closed during part of the forward feeding stroke of said fuel feeding piston to permit the pressure between said fuel feeding piston and said valve to be raised to a point above the pressure in the working 100 cylinder, said fuel feeding piston operating to open said valve near the end of the feeding stroke.
